TIMING SWITCH AND MECHANISM

Carl Ludwig Anderson, Moline, Ill., assignor to
Eagle Signal Corporation, Moline, Ill., a corpora-
tion of Massachusetts

Application September 14, 1936, Serial No. 100,825
Renewed August 9, 1939

26 Claims. (Cl. 200—33)

This invention relates to timing switches and mechanism and more particularly to switches embodying facilities for diversely timing the actuation of circuit controlling contacts with so-called "micrometer accuracy."

Timing switches constructed in accordance with this invention are well suited for determining the starting, running and stopping times of motors, groups of motors or the like, especially in instances where accurate determinations of times of occurrences of such activities are necessary.

An important object of this invention is to provide a timing switch, flexible as to operative characteristics, accurate as to the timing of characteristic occurrences, adjustable over wide ranges in relatively minute units of time, sturdy, compact and simple in design as well as durable and reliable.

A further object of this invention is to provide timing switches suited for the accomplishment of all, of any one or of any group of the foregoing objects, with maximum effectiveness and reliability, and having a minimum number of parts severally characterized by strength, durability, facility of assembly, and amenable to a low cost of manufacture.

Other and more specific objects and advantages will appear in the following description of an illustrative embodiment of this invention, or will be apparent to those skilled in this art.

Stated briefly, the operation is as follows: A pinion, responsive to a motor acting through a clutch and a train of gears, moves along a stationary threaded axle. A face associated with said pinion is effective upon attainment of a predetermined position on said threaded axle to engage and move a latch controlling a series of contact members.

A second pinion, also movable along the length of said stationary threaded axle, serves as a stop to limit movement of said first pinion in a direction away from such contact controlling face.

A spring, associated with said gear train, is tensioned when said first pinion is driven by the motor and restores said first pinion to its initial starting position, as determined by the adjustment of the second pinion on the threaded axle, when the clutch disengages the gear train from the driving motor. An electromagnetic operative means is used for engaging and disengaging the clutch and for raising the contact members permitting the latch to be restored to its initial position.

In the accompanying drawings,

Figure 1 represents a front elevation of a timing switch embodying a preferred aspect of this invention showing adjusting and contact mechanisms;

Fig. 2 represents a side elevation of the timing switch of Fig. 1 showing certain adjusting features;

Figs. 3, 4 and 5 are wiring diagrams schematically indicating certain arrangements of circuits in connection with which the switch of Figs. 1 and 2 may be utilized;

Figs. 6, 7 and 8 are charts diagrammatically indicating operating characteristics of said switch obtainable by circuit arrangements of Figs. 3, 4 and 5;

Figs. 9, 10, 11, 12, 13 and 14 are views indicating specific details of construction of said timing switch;

Figs. 15, 16, 17 and 18 are detail views more or less diagrammatically indicating several operative stages of said contact mechanism resultant from various adjustments of said timing switch; and

Figs. 19 and 20 are views indicating other specific details of construction of said timing switch.

The embodiment of this invention, as indicated in the accompanying drawings, is adapted to effect diverse conditionings of a plurality of circuit controlling contacts 101, 103, 105, 107, 109 and 111 (Fig. 1) in automatically or manually initiated timed cycles; the duration of certain of said conditionings being predetermined by adjustment of a knob 113 as will be hereinafter more fully explained.

The aforesaid timed cycles of conditionings are, in part, effected by a synchronous or chronometrically controlled motor 115 (Fig. 9) which acts to rotate a pinion 117 through a clutch comprising disengageable members 119 and 121; member 119 being fixed to motor shaft 125 for rotation therewith. A member 123 composed of some friction-aiding material, such as leather, may be placed between the members 119—121 to facilitate intended operation thereof.

Pinion 117 and member 121 are loosely journaled upon shaft 127 together with a shouldered sleeve 129; said sleeve being urged, by a coil spring 131, along said shaft 127 in such direction as to effect a pressure on clutch member 121 tending to carry said clutch member into engagement with clutch member 119.

As will be hereinafter more fully explained, a clutch fork 133 is adapted for at times engaging and moving a shoulder 135 on sleeve 129 thereby moving said sleeve in a direction effecting com-

pression of spring 131 and permitting disengagement of the clutch members 119-121 as indicated in Fig. 10.

Inasmuch as the pinion 117 and clutch member 121 rotate on the shaft 127 independently of the sleeve 129 and shoulder 135, the friction between said shoulder 135 and the clutch fork 133 during positioning for clutch disengagement, does not impede the freedom of movement of the 10 pinion 117.

A gear 137 engages pinion 117 for rotation therewith and has an end of a spring 139 secured thereto. The other end of spring 139 is secured to a frame post 141. Thus, as gear 137 is rotated 15 by motor 115, energy will be stored in the spring 139 for a purpose to be hereinafter explained.

An actuating pinion 143 has a threaded journal-orifice for association with a stationary, correspondingly threaded axle 145. Said pinion 143 20 engages gear 137 and, pursuant to motor driven actuation of said gear, is rotated and thereby axially moved, responsive to its threaded journal, toward a bifurcated contact conditioning lever 147 (see also Fig. 20).

25 Bifurcated lever 147 is freely journaled upon axle 145 and is biased by a spring 149 (Fig. 20) for counter-clockwise movement; a stop 151 being provided for limiting such movement.

Rotation of pinion 143 by the motor 115 causes 30 a face 155 associated therewith to engage a corresponding face 153 associated with said lever 147. Further rotation of pinion 143 will then cause rotation of lever 147 in a direction contrary to its bias, whereupon still further rotation 35 of said pinion 143 will be limited, as will be hereinafter more fully explained.

Rotation of pinion 143 causing it to move along axle 145 away from lever 147 is limited by an adjustable pinion 157 (Fig. 9). Like pinion 143, 40 pinion 157 has a threaded-journal association with axle 145 and has a face 159 for engagement with a corresponding face 161 associated with the end of pinion 143 opposite face 155.

Pinion 157 is adjustably positionable along the 45 length of axle 145 by rotation of an adjusting pinion 163. Pinion 163 and knob 113 (Fig. 9) are relatively fixed upon a shaft 165 so that rotation of knob 113 will effect corresponding rotation of pinion 163. When pinion 163 has attained a desired positioning, determined by indicia associated with knob 113 (see also Fig. 1), it may be there secured by tightening the clamping nut 167 against knob 113 as will be herein-after more fully explained.

50 The utilization of the faces 153, 155, 159 and 161 in accordance with this invention is of distinct importance in attaining wide-range accurate settings or adjustments of the operating characteristics of a relatively slow moving member.

In this respect it will be noted that the axial movement of pinion 143, pursuant to one revolution thereof, is but a distance equal to the pitch of the axle thread; however during the aforesaid 65 one revolution the faces 155 and 161 are moved angularly for 360 degrees. Thus when relatively slow axial movement of pinion 143 in one direction or the other carries either face 155 or face 161 into the path of respectively associated face 153 or 159 such faces approach and engage one another abruptly at a relatively high speed.

70 During disengagement of clutch members 119-121, energy stored in spring 139 becomes effective to produce counter-motor-actuated rotation of gear 137 and pinion 143 (and incidental-

ly of pinion 117) thereby causing said pinion 143 to be moved away from lever 147 and its face 161 to be moved into engagement with face 159 of pinion 157.

In assembly of the mechanism, adequate initial energy is stored in spring 139 to assure, at all instances of clutch disengagement, substantial urge by gear 137 for effecting counter-motor-actuated movement of pinion 143 sufficient for establishing engagement of the faces 159-161 irrespective of the axial positioning of pinion 157. It will be observed that energy stored in spring 139 will not deviate other than between predetermined limits as any motor-derived energy delivered to spring 139 incident to movement of pinion 143 in one direction will be dissipated during like movement of said pinion in the opposite direction.

The conditioning of the clutch 119-121 as effected by the clutch fork 133 is electromagnetically controlled.

As indicated in Fig. 13 movement of armature 169 is transmitted through link 173, arm 175, rock shaft 177, beam 179, pin 181, link 183 and pin 185 to a depending portion 187 of fork 133. 25 A member 189 so pivotally supports fork 133 that counter-clockwise rotative movement of portion 187 causes fork to effect clutch disengagement and clockwise movement permits clutch engagement.

With structure arranged as indicated in Fig. 13 downward movement of armature 169, responsive to energization of magnet coil 171, is transmitted through 173-175-177-179-181-183 and 185 to cause counter-clockwise movement 35 of portion 187 with consequent clutch disengagement. Conversely, upward movement of armature 169 responsive to the urge of armature spring 190 during deenergization of coil 171, effects positioning of fork 133 permitting clutch engagement.

Link 183 may be assembled to interconnect pin 185 with a pin 191 on beam 179, instead of with pin 181 on said beam, whereby such aforesaid downward movement of armature 169 effects clutch engagement and upward movement responsive to the urge of spring 190 effects clutch disengagement. The link is used in this position for certain operative arrangements hereinafter described.

50 As indicated in Fig. 20, lever 147 is subject to clockwise movement for causing a coacting finger 193 to swing an associated latch member 195 to what may be termed "unlatched" positioning.

Member 195 embodies upstanding projections 197 and 199 and lateral projections 201 and 203 for at times variously supporting insulated contact actuating blocks 205, 209, 211 and 213 respectively associated with contacts 101, 105, 60 107-109 and 111 and thereby at such times governing the conditioning of said contacts. A projection for contact block 207 and its associated contact 103 is not required as it is supported by contact 103 resting on contact 101 when member 195 is in the contact supporting or latched position illustrated in Fig. 20.

The actuating blocks 205, 207, 209, 211 and 213 are respectively supported by a series of arms 215 (most clearly exemplified in Fig. 14) which 70 are in turn pivoted upon a shaft 217.

A cradle 219 is also pivoted on shaft 217 and includes a variformed upturned edge 221 which underlies all the arms 215 (see also Fig. 17).

A second upturned edge 223 of said cradle 75

(Fig. 14) is associated with the rearward projections 227 of the various arms 215 through a series of compression springs 225, at the opposite side of said shaft 217 from edge 221 whereby the urge of said springs 225 will tend to swing the respective blocks 205, 207, 209, 211 and 213 in a clockwise direction (as viewed in Fig. 14) with the tendency or urge of bringing the arms 215 into engagement with the variformed edge 221 as indicated in Fig. 17.

A compression spring 229 (see Fig. 2) engages a rearward portion 231 of cradle 219 and a side plate 233 of the mechanism. By said spring the entire contact unit comprising cradle 219 and the assembled contacts is urged for counter-clockwise movement (as viewed in Fig. 2) to a position where a portion 235 thereof rests upon a projection 237 of said side plate 233.

As best indicated in Fig. 19, in connection with Figs. 13, 14 and 15, clockwise rotation of fork 133 to its clutch-disengaging position causes a lifting rod 239 to be raised, thereby bringing a shoulder 241 thereon into lifting engagement with a portion 243 protruding from cradle 219.

During such lifting engagement, each of the actuating blocks and their associated contacts will be supported by the cradle edge 221 at a height sufficient to permit free movement of all projections (197, 201, 199, 203) of latch member 195 underneath respectively associated actuating blocks (205, 209, 211, 213) (see Fig. 17). Such positioning of parts effected by support of the actuating blocks and their associated contacts by the elevated cradle edge 221 (above the member 195) will, for want of better expression, be hereinafter referred to as "elevated positioning".

During unlatched positioning of the latch member 195 (see Fig. 16), occurring after lever 141 has swung member 195 in a clockwise direction as hereinbefore described, contact blocks 205 and 207 are supported by the cradle edge 221 through their arms 215, 215, and the blocks 209 and 213 are respectively supported by the lateral projections 201 and 203 of the member 195; block 211 being supported by engagement of its associated contact 107 with contact 105. Such positioning of parts will, for want of better expression, be hereinafter referred to as "unlatched positioning."

Positioning of member 195 fully beneath the several contact blocks, causes all the contacts to be dependent upon member 195 for support. Such positioning of parts will, for want of better expression, be hereinafter referred to as "latched positioning."

Positioning of pinion 157 may be limited, in one direction, by abutment thereof against the mechanism front plate 245 (Fig. 9) and in the opposite direction following engagement of face 155 of pinion 143 with face 153 of arm 147.

The plate 245 has a groove 247 formed therein concentric with shaft 165. A ring shaped member 249 is positioned on said front plate concentric with said shaft 165 and has an annular projection 251 for engaging and freely sliding in the groove 247.

The pinion 265 has teeth 269 which extend across the entire face thereof and intermediate teeth 271 which extend across approximately half of said face. Said pinion 265 is carried by a stud 267 which is journaled in the front plate 245 for facilitating engagement of all of said teeth with the teeth 253 of the member 249.

The internal gear teeth 263, extending almost completely around the inner periphery of the

member 249 are suited for meshing with the teeth 269 and 271 of the pinion 265, as just indicated; there being, however, a tooth of extra thickness, with a slight indentation intermediate the circumferential extent thereof at 255, for blocking the rotation of the pinion 265 to prevent counter-clockwise rotation of the knob 113 which would carry the "0" indicia thereof past the "0" indicia of the ring shaped member 249 when the latter indicia is in alignment with reference 261 (see Fig. 1) and for preventing clockwise rotation of the knob 113 which would carry the "0" indicia thereon past the "20" indicia of the ring member 249 when said "20" indicia is in alignment with reference 261.

The disc 259 carried by the knob 113 has a pair of adjacent teeth 263 formed in the periphery thereof for cooperation with both the teeth 269 and the teeth 271 of the pinion 265, to provide an intermittent gearing drive whereby said member 249 will be rotated through an angular distance corresponding to two of the teeth 253 incidental to each revolution of the knob 113.

The disc 257 is also carried by the knob 113, and is formed and situated for cooperation with the teeth 269 only. As the diameter of disc 257 is larger than disc 259, the pinion 265 cannot be rotated unless a tooth 269 is engaged by the cut-away portion of disc 257 between the teeth 263 of disc 259. This prevents movement of pinion 265 and of ring 249 except when teeth 263 mesh with teeth 269 and 271.

As indicated in Fig. 1, indicia upon the ring-shaped member 249 are indicative of the number of revolutions which knob 113 has been rotated from a fixed reference point and indicia on the knob 113 at 273 (Fig. 9) are indicative of portions of a revolution of said knob from a fixed reference point.

The ratio between pinions 157 and 163, the speed of motor 115 and the gear ratio of train 117—137—143 preferably is such that one revolution of knob 113 will move pinion 157 along the threaded axle 145 a distance exactly equal to that which motor 115 will move pinion 143 in precisely one minute of time.

Furthermore, the relative arrangement of the various parts and the applied indicia is such that the pinion 157 may be moved along the threaded axle 145 by rotation of the knob 113, and that the indicia of knob 113 and ring 249 will, for any setting of said knob, be representative of the exact time required for the motor 115, through rotation of the pinion 143, to carry the face 161 away from the face 159 and thereafter cause actuation of the arm 147 when the face 153 has been engaged by the face 155.

For the time switch shown, such timing may be preset in divisions of one second, or readily discernible fractions thereof, for durations to and including twenty minutes.

Settings may be retained by rotating the nut 167 along the threaded end of shaft 165 so as to cause the knob 113 to clamp the ring member 249 against the front plate 245.

As best indicated in Fig. 19, lifting rod 239 is pivoted at 275 upon the portion 187 of fork 133. A spring 277 is so applied to rod 239 as to urge rotation thereof such as will swing the shoulder 241 out of the path of the portion 243 of cradle 219. However, a screw stud 279, assembled in the side of the cradle 219, is provided for retaining shoulder 241 in the path of portion 243, which stud 279 may be removed for certain types of service, as will be hereinafter explained.

When, as indicated in Fig. 15, the parts of the contact structure are in "latched position" contacts 101-103 and contacts 109-111 will be closed while contacts 105-107 will be open.

6 During the heretofore described "unlatched positioning" of the latch member 195 (see Fig. 16), contacts 105-107 will be closed and contacts 101-103 and 109-111 will be open.

During the heretofore described "elevated positioning" of the contact structure, (see Fig. 17) only contacts 109-111 will be closed.

As indicated in Fig. 18, a plug 281 may be assembled in the cradle 219 in association with the arm 216 which supports block 213. So assembled 15 such plug forms, in effect, an alteration in the contour of the upturned edge 221 such that, during "elevated positioning" of the contact structure, all the contacts will be open.

With parts as thus far described, lifting of the 20 bar 239 will always lift the contact structure; however, in certain operative situations it is desirable that the contact structure shall be lifted responsive to the bar 239 only during unlatched positioning of latch member 195.

25 In order that the mechanism shown may be satisfactorily employed in such situations, the screw stud 279 is made removable, as already indicated, and a finger 283 is carried by the bar 239 (see Figs. 13, 19 and 20) for cooperation with

30 an extension 285 carried by the latch member 195. Thus, in the absence of said stud 279, latch positioning of said latch member will permit said bar 239 to assume a position, responsive to its spring 277, in which said shoulder 241 will be

35 withdrawn from beneath portion 243 of cradle 219, while unlatched positioning of said latch member 195 will cause extension 285 to act through finger 283 to position bar 239 so that its shoulder 241 is under said portion 243.

40 The following description indicates some of the many ways in which the mechanism herein described may be utilized.

For example, assume that such a mechanism is connected to terminals 301, 303, 305, 307, 309

45 and 311 as indicated in Fig. 3 and that a bridging member 313 interconnects terminals 303 and 311.

50 As there indicated, magnet 171 and motor 115 are in parallel current paths across terminals 301 and 303; contact 103 is connected to terminal 303 and contacts 101 and 107-109 are connected to terminal 305. Contacts 105 and 111 are respectively connected to terminals 307 and 309 for effecting time control of external circuits 55 as may be desired. A normally open-circuit push button 315 is connected across terminals 303 and 305. Conductors 317, 318, are for connecting a suitable source of current supply to terminals 301 and 305.

60 Further assuming that link 183 is installed to interconnect pins 185-181 (Fig. 13), that screw stud 279 is installed (Fig. 19) and that plug 281 is placed in the cradle 219 (Fig. 18); during "rest" or "home" conditioning of the mechanism, clutch 119-121 (Fig. 9) will be disengaged, pinion 143 will be moved by spring 139 away from arm 147 into engagement with adjusting pinion 157, and the various contacts will be open because of elevated positioning of the cradle and 65 contact structure as indicated in Fig. 18.

If now the knob 113 has been rotated so that the indicia 273 carried thereby and that carried by the ring member 249 is indicative of a desired operating time, and the push button 315 is closed, 70 magnet 171 and motor 115 become energized and,

as indicated in Fig. 15, the contacts assume their latched positioning. The contacts 101-103 thus establish a so-called "holding path" for maintaining energization of magnet 171 and of motor 115. Contacts 109-111 are closed during this period 5 and are available for controlling an external circuit. Such latched positioning of contacts will persist for the time indicated by the presetting of the indicia and measured by the motor actuated movement of pinion 143 along axle 145 toward 10 arm 147 (Fig. 9).

At the expiration of the preset time, face 155 of pinion 143 effects movement of arm 147 to carry latch 195 to its unlatched positioning whereupon the various contacts attempt momentarily 15 to assume the condition indicated in Fig. 16 wherein all contacts are open except contacts 105-107. However, immediately upon the opening of contacts 101-103, magnet 171 and motor 115 become deenergized, clutch 119-121 opens, 20 pinion 143 moves, responsive to spring 139, into association with pinion 157, and cradle 219 assumes elevated positioning and the contacts and mechanism again attain the heretofore mentioned "rest" or "home" position indicated in Fig. 25 18.

Since, in the aforescribed cycle of operation, any attained closure of contacts 105-107 will be of very short duration, it may be assumed that such cycle of contact conditionings comprises two 30 components, namely an indefinite "rest" or "home" period extraneously controlled during which all contacts are open (Fig. 18) and a timed period of preset duration throughout which contacts 101-103 and contacts 109-111 are respectively closed (Fig. 15).

Such cycle of contacts conditionings is represented by the chart of Fig. 6 wherein the horizontal lines 323 and 327 represent closed conditioning durations of contacts 101-103 and 40 109-111, respectively, the space between vertical lines 329-331 represents the short period of time of elevated positioning of the contacts during which push button 315 is held closed, the space between lines 329-333 represents the timed movement effected by pinion 143 during latched positioning of the contacts and the space between lines 333-335 represents the indefinite time of unlatched, open-circuit conditioning of the contacts. 50

With all parts installed and assembled as heretofore described but with bridging member 313 removed and with a normally closed push button 321 replacing normally open push button 315, all as indicated in Fig. 4, the operative cycle of the 55 contacts becomes as indicated by the chart of Fig. 7; such cycle being initiated by opening the contacts of push button 321. In this chart the horizontal line 325 represents closed circuit conditioning of contacts 105-107. The space between vertical lines 329-331 represents the duration of elevated positioning of the contacts during which push button 321 is held open. The space between lines 331-333 represents the timed movement effected by pinion 143 during latched 65 conditioning of the contacts and the space between lines 333-335 represents the indefinite duration of unlatched conditioning of the contacts.

With the circuit arrangement as indicated in 70 Fig. 4 but with the plug 281 removed, the operative cycle of the contacts will be as indicated by the chart of Fig. 8.

Another type of operative cycle may be established by placing link 183 (Fig. 13) for inter- 75

connection of pins 181—185, by removing screw stud 279 and by utilizing a normally open push button 315 (Fig. 5). With such arrangement the contact conditioning cycle will be as indicated by the chart of Fig. 7. If, in addition, the plug 281 is also removed, the contact conditioning cycle will be as indicated by the chart of Fig. 8.

In those instances herein described wherein a normally closed push button is utilized, in case of power failure at conductors 317—319 the mechanism will revert to its "rest" or "home" position, so as to require manual actuation of the push button 321 after restoration of power supply to effect resumption of cyclic activity. Such is also the case in the first instance described where a normally open push button is utilized and the link 183 interconnects pins 185 and 191.

In the last instances wherein link 183 interconnects pins 181—185, and either screw stud 279 or both stud 279 and plug 281 are removed, the mechanism will not, in case of power failure, revert to its starting position but will resume its unfinished cycle when power is restored, without supplemental push button actuation.

Having now described my invention, I claim:

1. In a timing switch,—a plurality of circuit conditioning members involving a pair of contacts one of which is biased for movement toward circuit closing position and the other for movement toward circuit opening position and a triplicity of contacts having one contact biased for movement away from a second and toward a third contact, said second contact being biased for movement toward and said third being biased for movement away from said one contact of said triplicity; a latch member movable against a bias from one to another position and associated with said circuit conditioning members for supporting certain of said contacts in latched positions during one latch member positioning and for supporting certain others of said contacts in unlatched positions during another latch member positioning; a supporting cradle for said contacts movable for supporting said contacts exclusive of said latch member; a threaded axle having a fixed and an adjustable limit thereon; an actuating pinion having a threaded engagement with said axle and revoluble for effecting movement thereof along said axle between said limits; motor means associated with said pinion for effecting rotation thereof for relatively slowly moving said pinion into engagement with said fixed limit; means responsive to engagement of said pinion and said fixed limit for effecting relatively rapid movement of said latch member from said one to said other position; means for storing energy responsive to motor means activity of said pinion; means operable for disassociating said motor from said pinion and for moving said cradle into contact supporting relationship permissive of bias urged movement of said latch member; and means responsive to activity of said operable means for rendering effective said energy storing means for causing movement of said pinion away from said fixed limit into engagement with said adjustable limit.

2. In a timing switch,—a plurality of circuit conditioning members including a pair of contacts one of which is biased for movement toward circuit closing position and the other biased for movement toward circuit opening position and including a triplicity of contacts one of which is biased for movement away from a second and toward a third of said triplicity of contacts, said second contact being biased for movement toward

said one of said triplicity and said third biased for movement away from said one of said triplicity; a latch member movable from one to another position for diversely conditioning said pair and said triplicity of contacts; a synchronous motor; a gear train driven by said motor; a clutch interposed between said motor and said train; a pinion included in said gear train and, responsive to rotation thereof, movable along its axis between a fixed and an adjustable stop; means for varying the distance between said fixed and said adjustable stops; means responsive to engagement between said pinion and said fixed stop for effecting movement of said latch; a spring associated with said gear train for tensioning pursuant to latch moving activity of said pinion and means including electromagnetic structure for at times effecting released conditioning of said clutch whereby said spring effects rotative and axial movement of said pinion away from said fixed stop and toward said adjustable stop.

3. In a timing switch,—the combination of a plurality of current path circuit controllers each having operable circuit opening and closing members; latch means effective for supporting said members in one relationship; means permitting bias urged attainment of another circuit member relationship involving means for rendering said latch means ineffective, said last named means comprising an actuating member having a relatively slow component of movement and a relatively fast component of movement from an initial rest position and having a terminating position therefor; chronometrically controlled motor means for effecting both and controlling the speed of one of said component movements; an actuating part for operation by said motor means responsive to attainment of said terminating position by said actuating member for moving said latch means to an ineffective position; manual means for preestablishing the extent of one of said actuating member movement components whereby to determine the duration of said one circuit member relationship; means for restoring effectiveness of said one circuit member relationship following attainment of said other circuit member relationship, for restoring said latch member to supporting position and for restoring substantially instantaneously said actuating member to its initial rest position; and means effecting a third circuit member relationship incidental to activity of said last named restoring means.

4. A timing switch having, in combination, preconditioned mechanism comprising a plurality of bias urged contact members, latch means effective for maintaining said contact members positioned contrary to their bias, actuating means operable contrary to a bias for rendering said latch means ineffective, time controlled means for operating said actuating means, said time controller means comprising a timing member biased toward a starting position and axially movable therefrom responsive to rotation thereof into operable relationship with said actuating means, chronometric means adapted for at times rotating said timing member, means responsive to operable relationship of said timing member with said actuating means for rendering effective rotative movement of said timing member for operating said actuating means to render said latch means ineffective, adjusting means for predetermined said starting position of said timing member whereby to predetermine the time duration occurring during movement of said timing

member from its starting position to its actuating-means-operating position, and means for restoring preconditioning of said mechanism.

5. Timing mechanism having, in combination, a threaded axle, a pinion having a threaded journal-orifice therethrough and axially movable along said axle between a fixed and an adjustable limit responsive to rotation thereof, time governed power means associated for rotating said 10 pinion whereby to effect relatively slow axial movement thereof into engagement with one of said limits, means associated with said one of said limits for actuation consummating a timed operation, means associated with said pinion for effecting relatively fast actuation of said consummating means responsive to engagement of said pinion with said one limit, means for disassociating said power means from said pinion, and means for moving said pinion out of engagement 15 with said one limit and into engagement with the other of said limits.

6. In a timing switch, circuit controlling contacts having a normal relationship, motor means, means associated with said motor means and movable thereby from one to the other of two limits at a predetermined speed, means responsive to movement of said associated means while adjacent to one of said limits for effecting alteration of said contact relationship, manually presettable means for changing the position of one of said limits whereby to change the required time duration for movement of said associated means from said one to the other of said limits, said changing means involving an indicia bearing knob, 30 an associated indicia bearing member, and an intermittent gearing connection between said knob and said member whereby their indicia will indicate the extent of rotation of said knob.

7. In a timing switch, the combination of a plurality of switches each including a movable contact member, actuating means including a pinion having threaded engagement with a threaded axle and an actuating face rendered effective responsive to axial movement of said 40 pinion for effecting movements of said movable contact members from one condition to another condition following continuance of said one condition for a predetermined duration of time, power means, power transmitting mechanism interposed between said power means and said actuating means for rotating the latter and thereby effecting axial movement thereof, a spring associated with the said mechanism arranged for storing energy during the rotation of the actuating 50 means by the power means, and means for releasing the stored energy to restore said actuating means to its initial position along the threaded axle.

8. A timing switch comprising a plurality of 60 actuatable circuit governing contacts in combination with a part involving a threaded axle, and a rotatable member having a threaded orifice journaled upon said axle and movable from a variable predetermined starting position to a fixed contact actuating position, means for storing energy during movement of said part to contact actuating position and means rendering said stored energy effective for restoring said part to its variable predetermined starting position.

70 9. A timing mechanism having, in combination, a member actuatable after the expiration of a predetermined time interval, a threaded axle, a pinion having a threaded journal-orifice for engaging said axle, time controlled means for 75 rotating said pinion whereby to effect axial move-

ment thereof into engagement with said member, means associated with said pinion and responsive to engagement thereof with said member for rendering rotative movement of said pinion effective for actuating said member, means for storing energy during the movement of said pinion to the actuating position, means for rendering stored energy effective for restoring said pinion to its variable predetermined stopping position, and means for adjusting said stopping position comprising, in part, a rotatable dial and an associated indicia bearing member having a gearing connection with said dial for movement of said dial. 10

10. A switching mechanism having, in combination, contacts, a threaded axle, a member rotatable upon said axle and engaging the thread thereof, means for effecting actuation of said contacts responsive to rotation of said member in one direction upon attainment of a predetermined axial position, driving means, including an electro-responsive means and an intervening clutch, for rotating said member and thereby effecting axial movement thereof toward said predetermined position, means yieldingly urging rotation of said member in a direction for effecting axial movement thereof away from said predetermined position, and manually presettable means for variously establishing extents of rotation of said member in said second named direction. 15

11. A switching mechanism having, in combination, means for actuating a plurality of circuit governing contacts, a threaded axle, a pinion having a threaded journal orifice for engaging said axle, rotative means for rotating said pinion whereby to effect axial movement thereof into engagement with the first named means, means associated with said pinion and responsive to engagement of said pinion associated means with said first named means for rendering rotative movement of said pinion effective for actuating said first named means, and means for restoring said pinion to a predetermined position on said axle independently of said rotative means. 20

12. In a timing mechanism controlled by a switch for closing an electric circuit, the combination of a plurality of circuit-closing means; a threaded axle; a member revolvable upon said axle and engaging the thread thereof; means for effecting actuation of said circuit-closing means to an open or closed condition responsive to rotation of said member in one direction and upon attainment of a predetermined axial position by said member; a driving means for rotating said member; a connecting means between said driving means and said member comprising, in part, a clutch; an electromagnet responsive to closure of said control switch to cause said clutch to become engaged to connect the driving means with said member; a positioning means for normally positioning certain of said circuit-closing means in an open position and responsive to actuation of said electromagnet for positioning certain of said means in a closed position, one of said closed circuit-closing means being adapted to complete a holding circuit for said electromagnet during the timing interval; and means for storing energy during the rotative movement of said pinion by said driving means, the said stored energy being effective to return said member to its initial position along the threaded axle when the actuating means reacts to open certain of said circuit-closing means. 25

13. In a timing mechanism controlled by an electric switch, the combination of a plurality of 30

70

5 circuit-closing means; an operable means which it is desired shall be operated after the lapse of a predetermined period of time for opening or closing the said circuit-closing means; a positioning means for positioning said circuit-closing means in an unresponsive relation with said operable means; a threaded axle; a member revolvable upon said axle and engaging the thread thereof and effective, upon reaching a predetermined axial position, for operating said operable means; a motor; connecting means between said member and said motor, including, in part, a clutch normally disengaged; an electromagnet operatively connected with said positioning means 10 and responsive to closure of said switch, the said electromagnet, when energized, moving said positioning means so that said circuit-closing means is in a responsive relation with said operable means and moving said clutch to an engaged 15 relation to render the revolvable member responsive to the motor; and a spring restoring means for returning said member to its initial position when the said electromagnet is deenergized.

14. In a timing mechanism controlled by an 20 electric switch; operable means which it is desired shall be operated after the lapse of a predetermined period of time; a threaded axle; a member revolvable upon said axle and engaging the thread thereof and effective upon reaching a predetermined axial position for operating said operable means; a motor; connecting means between said member and said motor whereby the movement of said member in one direction is controlled by said motor; spring means for restoring said member; limiting means comprising, in part, a movable stop for determining the extent of the restoring movement of said member; means for adjusting the position of the limiting means; and means responsive to closure of said 25 control switch for releasing the connecting means between said member and said motor for permitting the spring-return movement of said member to the position along the axle as determined by the position of said stop.

45 15. In a timing mechanism controlled by an electric switch; operable means which it is desired shall be operated after the lapse of a predetermined period of time; a threaded axle; a member revolvable upon said axle, engaging the thread thereof, and effective, upon reaching a predetermined axial position, for operating said operable means; a motor; connecting means between said member and said motor whereby the movement of said member in one direction is controlled by said motor; spring means for restoring said member to the starting position for its motor-controlled movement; and means for releasing the connecting means between said motor and said member upon closure of said control switch 60 for permitting the return movement of said member.

65 16. In a timing switch, a circuit controller for opening or closing an electric circuit, an operable means which it is desired shall be operated after the lapse of a predetermined period of time, the said circuit controller being during timing operation held in a circuit-closing position by the operable means, a movable member for operating said operable means, a driving motor, a connecting means between said movable member and said driving motor, an electromagnetically operated means for controlling the said connecting means between said member and said driving motor, a restoring means to return said movable member to the starting position of its motor-con-

trolled movement, and a positioning means controlled by said electromagnetic means for positioning said circuit controller in an unobstructing position in relation to said operable means to permit the return of said operable means to its normal position, the said positioning means being responsive to said electromagnet only after the operable means has been operated by the movable member.

5 17. In a time-controlled mechanism, a timing 10 motor, operable means which it is desired shall be operated after the lapse of a predetermined period of time, a threaded axle, a member revolvable upon said axle and engaging the thread thereof and effective upon reaching a predetermined axial position for operating said operable means, means whereby the rate of movement of said member in one direction is controlled by said motor, spring means for returning said member after its motor-controlled movement, a threaded 20 stop revolvable upon said axle for limiting said return movement to predetermine the extent of the motor-controlled movement, a calibrated dial member, a gearing connection between said stop and said dial whereby rotation of said dial rotates 25 said threaded stop about the threaded axle, and an indica-bearing member associated with said dial for indicating the number of revolutions that the said dial is turned.

18. In a timing switch, the combination of 30 contact switch members, one of said members being biased toward a circuit closing position and another of said members being biased toward a circuit-opening position; an electromagnet; a member operated by said magnet for lifting said 35 contact members against their bias; tripping means for holding the contact members against their bias; timing means; means effective upon the expiration of a predetermined time interval for moving said tripping means away from the 40 holding position for said contact members, permitting them to assume their bias-urged position; a stop for limiting the bias-urged movement of said members; and means to restore said tripping member to its holding position when the 45 contact members are lifted by the lifting member.

19. In a switching mechanism, the combination comprising an externally threaded member, an internally threaded member in screw-threaded 50 engagement therewith, actuating means for effecting actuation of a plurality of circuit contacts having a portion of said actuating means positioned to be actuated by one of said members, rotative means for producing relative rotation 55 between said members whereby said one of said members is moved into position to actuate said actuating means, drive means operatively connecting said rotative means and said one of said members, and means responsive to actuation of 60 said actuating means by said one of said members for disengaging said drive means.

20. In a switching mechanism, the combination comprising a threaded axle, a pinion in screw-threaded engagement with said axle, actuating 65 means for effecting actuation of a plurality of circuit contacts having a portion of said actuating means positioned to be actuated by said pinion, rotative means for relatively rotating said pinion and axle whereby said pinion is moved into 70 position to actuate said actuating means, drive means operatively connecting said rotative means and said pinion, means responsive to actuation of said actuating means by said pinion for disengaging said drive means, and spring means to 75

move said pinion along said axle when said drive means is disengaged and in the opposite direction from which it is moved by said drive means.

5 21. In a switching mechanism, the combination comprising an externally threaded member, an internally threaded member therewith engaging for movement therealong upon rotation of the second member, a driving means for rotating

10 said second member in one direction, a clutch through which said drive means rotates said second member and operative to disengage said means and said second member, and an actuated means in a predetermined operatively fixed position

15 longitudinally of the first member actuated in response to rotative movement of said second member.

22. In a switching mechanism, the combination comprising an externally threaded member,

20 an internally threaded member therewith engaging for movement of one of said members along the other upon rotation of said one of said members, a driving means for rotating said one of said members in one direction, a clutch

25 through which said drive means rotates said one of said members and operates to disengage said one of said members and said drive means, and an actuated means actuated responsive to rotative movement of said one of said members po-

30 sitioned in a predetermined operatively fixed position along the line of movement.

23. In a switching mechanism, the combination comprising an externally threaded member, an internally threaded member therewith engag-

35 ing for movement therealong upon rotation of the second member, a driving means for rotating said second member in one direction, a clutch through which said drive means rotates said sec-

40 ond member and operative to disengage said means and said second member, an actuated means in a predetermined operatively fixed position

45 longitudinally of the first member actuated in response to rotative movement of said second member, and means yieldingly urging ro-

50 tation of said second member in a direction away from said actuated means operative upon

55 disengagement of said clutch.

24. In a switching mechanism, the combination comprising an externally threaded member,

50 an internally threaded member therewith engaging for movement therealong upon rotation of said second member, a driving means for rotat-

55 ing said second member in one direction, a clutch through which said drive means rotates said sec-

ond member and operative to disengage said means and said second member, an actuated means in a predetermined operatively fixed po-

55 sition longitudinally of the first member actu-

ated in response to rotative movement of said second member, means yieldingly urging rotation of said second member in a direction away from said actuated means operative upon disengagement of said clutch, a stop for limiting movement of said second member under operation of said second means, and means to adjust the spacing of said actuated means and said stop along said first member.

5 25. A switching mechanism, comprising a plu-

10 rality of cooperating pairs of switch elements, controlling means to control the conditioning of said pairs and upon actuation of said controlling

15 means to change the circuit conditioning of said pairs, holding means to hold said elements in a position non-responsive to said controlling

means and to control the circuit conditioning of said pairs while in such position, a motor, com-

mon means to initiate motor controlled actuation of said controlling means and to render said 20 holding means ineffective for holding, said control-

25 ling means including a member rotatable by said motor and a spring to effect rotation of said member in the opposite direction from that in

which it is driven by said motor, and a pair of 25 stop-members cooperating with said member and between which said member rotates, one of said stops being adjustable to vary the extent of

30 rotation of said member between said stops, termination of rotation by contact of said member with one of said stops to which it is driven by said motor effecting change of the circuit condition-

35 ing of at least one of said pairs by said control-

40 means.

26. A switching mechanism comprising a plu-

45 rality of pairs of cooperating switch elements, controlling means to control the circuit conditioning of said pairs of switch elements when said contacts are in responsive relation thereto

50 and upon actuation of said controlling means in one direction to change the circuit conditioning of at least one of said pairs, said one of said pairs, when said elements are in responsive re-

55 lation to said controlling means, after actuation of said controlling means, preventing movement of said controlling means in a direction opposed

50 to the movement thereof during actuation, means for moving said controlling means in said op-

55 posed direction when said elements are in a po-

60 sition non-responsive to said controlling means, holding means to move said elements into and to hold said elements in said position non-re-

65 sponsive to said controlling means, a motor, and common means to initiate motor controlled actua-

70 tion of said controlling means and to render said holding means ineffective for holding.

CARL LUDWIG ANDERSON.
